SHREDDING APPARATUS

Robert W. Stevenson, Columbus, Ohio, assignor
to The Jeffrey Manufacturing Company, a cor-
poration of Ohio

Application March 19, 1932, Serial No. 599,981

6 Claims. (Cl. 83—75)

My invention relates to apparatus for shredding wood or other material, and one of its objects is the provision of improved and efficient mechanism for dividing the material to be shredded, and feeding such divided material into a shredder.

Another object of the invention, is the provision of improved and efficient means for collecting the cuttings, or sawdust, of the material which is divided, and feeding the same into the shredder.

More particularly, it is the object of the present invention to provide a gang of rotary saws, in spaced apart relation, for dividing slabs of wood into such small pieces as to be readily acted upon by a shredder, into which such small pieces are fed from the saws. Other objects of the invention will appear hereinafter, the novel features and combinations being set forth in the appended claims.

In the accompanying drawing, Fig. 1 is an elevation, partly in section, of shredding apparatus embodying my improvements.

Fig. 2 is an enlarged sectional elevation taken on the line 2—2 of Fig. 1, looking in the direction of the arrows.

In Fig. 1, I have shown a rotary shredder 3 of the swinging hammer type, comprising a multiplicity of centrifugally operated hammer arms 4, mounted on the rotary drum 5, which is keyed to the shaft 6 so as to rotate in the direction of the arrow 7. An adjustable breaker plate 8 is mounted on the pivoted frame 9, so as to move bodily therewith, when adjusted by means of the adjusting screw 10. Spaced shredding cutters 11 are located in the bottom of the shredder 3.

The upper side of the shredder 3 is provided with a hopper 12 for receiving the small pieces of wood which are obtained by operating the gang of saws 13 on the slabs of wood or other material 14.

On the supporting frame-work 15 is mounted a feed table 16, having parallel slots which are spaced apart so as to alternate with the saws 13.

On the upper portion of the frame 15 is mounted feeding mechanism comprising a plurality of spaced apart sprockets 17 and 18, respectively keyed to the shafts 19 and 20. Endless sprocket chains 21 mesh with the sprockets 17 and 18, and each chain is provided with feeding teeth 22 in position to extend into and above the slots in the feed table 16. As shown in Fig. 1, the feeding teeth project above the upper surface of the feed table 16 a sufficient distance to engage the rear edge of the slab of wood 14.

A large spur gear 23 is secured to the shaft 19 in position to mesh with the small spur gear 24 on the shaft 25 which is mounted on top of the frame 3' of the shredder 3. To the left-hand end of the shaft 25 as viewed in Fig. 2 is connected a pulley 26 having thereon an endless belt 28 which extends upwardly over the pulley 29 on the shaft 30. At the upper ends of the standards 31, 32 are mounted the bearings 34, 35 for the shaft 30. Secured to the shaft 30 are the rotary saws 13 with spacers 36 between the saws and the bearings and between adjacent saws.

The rotary crusher 3 is adapted to be driven by a motor connected to the shaft 6 to drive the swinging hammers 4 in the direction of the arrow 7. A pulley 37 on the shaft 6 is connected by means of the endless belt 38 to the pulley 33 on the shaft 30. The driving of the shaft 6 in an anti-clockwise direction as viewed in Fig. 1 will result in the rotation of the circular saws 13 in the direction of the arrow 45. At the same time the shaft 25 will be driven in an anti-clockwise direction, but because of the gears 24 and 23 the shaft 19 will be driven in a clockwise direction. Consequently the spaced-apart endless feed chains 21 will be driven in the direction of the arrow 27 so that when the teeth 22 engage the slabs 24 the latter will be carried or fed to and along the gang of saws 13.

The direction of rotation of the circular saws 13 as indicated by the arrow 45 is such as to tend to throw the sawdust rearwardly toward the wall 46 of the enclosure 47, so as to cause the sawdust to fall into the hopper 12 from which it is free to pass through the screen 11 at the bottom of the shredder and into the pan 41.

The enclosure 47 comprising the upright wall 46, the horizontal plate 48 and the saw cover 49, serve to prevent the sawdust due to the sawing operation from spreading into the outside atmosphere.

In the front side of the enclosure 47 is an elongated opening 50 of sufficient height and length to permit the largest slabs of wood 14 to enter the space in advance of the saws. Openings are provided at 39 in the feed table 16 immediately below the saws, to permit the heavier particles of the sawdust to drop by gravity into the pipe 40 which communicates at its lower end with the pan 41. The sawdust received from the pipe 40 and from the screen 11 at the bottom of the shredder 3 may be directed into the delivery pipe 42 in the direction indicated by the arrow 43, by any desired means. A vertical sliding door 44 at the front end of the pan 41 controls an open-

ing through which the bottom of the pan 41 may be cleaned or accumulated material withdrawn.

The rear end of the feed table 16 extends beyond the saws 13 as shown in Fig. 1. Spring-pressed holders each comprising a trough-shaped plate 51 and a finger 52 are provided at both sides of each saw, to hold against the feed table the small pieces of wood until after they leave the spaces adjacent to the saws, thereby assuring complete sawing, preventing the splitting off of long pieces of material and preventing small sawed pieces from becoming jammed between the saws.

Each finger 52 is pivoted at 53 and is urged downwardly by means of a spring 54 on a bolt 55. The lower end 56 of the bolt 55 acts to limit the downward movement of the finger 52. By means of a nut 57 the position of the finger 52 may be adjusted.

Each finger 52 engages the upper side of a corresponding trough plate 51 which is carried on an arm 58 pivoted at 59.

As shown in Fig. 2 each saw is provided at both sides thereof with a spring-pressed holding device each comprising the presser plate 51, the finger 52 and the spring 54. The presser plates 51 are appreciably narrower than the spaces between the saws and are therefore free to move upwardly and downwardly in accordance with the thickness of the slab 14 of the material being cut into small pieces. The presser plates hold the small pieces of material in contact with the feed table until they leave the spaces between the saws. The small pieces of sawed material are then fed to the rear end of the table 16 and dropped into the hopper 12.

The shredder 3 is of well-known construction but shredders of this type are not adapted to operate on slabs of wood cut from green logs. Such slabs are too large to be fed into shredders of this type and I have therefore combined with the shredder shown the apparatus for cutting the slabs into small pieces and collecting the sawdust produced during such dividing operations. Although I have shown the gang of saws and the feeding mechanism operated by connections extending from the shaft 6, the feeding and sawing operations may be effected by means of a separate motor, if desired.

Obviously those skilled in the art may make various changes in the details and arrangement of parts without departing from the spirit and scope of the invention as defined by the claims hereto appended and I wish therefore not to be restricted to the precise construction herein disclosed.

Having thus described and shown an embodiment of my invention, what I desire to secure by Letters Patent of the United States is:

1. In shredding apparatus, the combination with a shredder, of multiple sawing mechanism, a hopper for delivering the sawed material to said shredder, a housing for enclosing said sawing

mechanism and covering the space above said hopper, a collector below said shredder, a pipe connecting the space below said sawing mechanism with said collector, and means for driving said sawing mechanism in a direction to assist in delivering the sawed material to said hopper and the sawdust to said pipe.

2. In shredding apparatus, the combination with multiple sawing mechanism, of a shredder associated therewith, a hopper for said shredder, a housing covering said sawing mechanism and the space above said hopper, means for feeding material into said housing beneath said sawing mechanism and to said hopper, a collector beneath said shredder, and a sawdust collector extending from said sawing mechanism to said shredder collector.

3. In shredding apparatus, the combination with sawing mechanism, of a shredder, a hopper for said shredder, a housing covering said sawing mechanism and the space above said hopper, a collector beneath said shredder, a feed table extending into said housing beneath the axis of rotation of said sawing mechanism, means associated with said table for feeding material to said sawing mechanism, and a sawdust flue extending between said sawing mechanism and said collector.

4. In shredding apparatus, the combination with a shredder, of a plurality of spaced saws, a table feed mechanism below the said saws, an enclosure for the saws, a hopper between the enclosure and shredder, a pan beneath the shredder communicating therewith, and a conduit extending from the pan and opening adjacent the saws, the said conduit conducting sawdust from the saws to the pan, and the pan receiving sawdust passing through the hopper and shredder.

5. In shredding apparatus, the combination with a shredder, of multiple sawing mechanism, a hopper for delivering the sawed material to the shredder, a housing for enclosing the sawing mechanism and covering the space above the hopper, a collector below the shredder, a pipe connecting the space below the sawing mechanism with the collector, and means for driving the sawing mechanism in a direction to assist in delivering the sawed material to the hopper and the sawdust to the pipe.

6. In shredding apparatus, the combination with sawing mechanism, of a shredder, a hopper for the said shredder, a housing covering the sawing mechanism and the space above the said hopper, a collector beneath the shredder, a feed table extending into the housing beneath the axis of rotation of the sawing mechanism, means associated with the table for feeding material to the sawing mechanism, and a sawdust flue extending between the sawing mechanism and the collector.

ROBERT W. STEVENSON.
